Harry Weaver,

UNITED STATES PATENT OFFICE.

HARRY WEAVER, OF YORK HAVEN, PENNSYLVANIA.

JAR-CLOSURE.

1,250,058.

Specification of Letters Patent. Patented Dec. 11, 1917.

Application filed December 29, 1916. Serial No. 139,557.

To all whom it may concern:

Be it known that I, HARRY WEAVER, a citizen of the United States, residing at York Haven, in the county of York and State of Pennsylvania, have invented new and useful Improvements in Jar-Closures, of which the following is a specification.

The present invention contemplates the provision of a novel type of jar closure primarily adapted for use on fruit jars.

The primary object of the invention resides in the production of a closure of the above stated character so designed whereby upon the application of the closure to the jar, will perform a positive and effective sealing of the jar in order to exclude the entrance of air to the contents thereof.

To this end, use is made of a sectional cap so constructed whereby upon the opening of the cap or closure will necessitate lifting of the gasket from the mouth of the jar, thus preventing any liability of breaking the jar during the opening action of the cap.

Furthermore, it is my object to provide one of the cap sections with a locking bar, whereby upon the assemblage of the cap sections, the locking bar will serve to hold the same together and cause a lifting action to be imparted to the sealing gasket to release its engagement with the outer circumference of the mouth of the jar.

With the above and other objects in view, the invention consists in the novel features, details of construction and combination of parts which will hereinafter be more fully set forth, illustrated in the accompanying drawing and pointed out in the appended claim.

Figure 1 is a detail perspective view of a portion of a jar showing the closure applied thereto;

Fig. 2 is a view similar to Fig. 1 illustrating the closure in perspective and the parts constituting the cap in separated position; and

Fig. 3 is a bottom plan view of the inner section of the cap.

Fig. 4 is a detail view illustrating the application of the closure to the neck of a fruit jar, the neck, and one of the sections of the closure being illustrated in vertical section.

Referring more particularly to the accompanying drawing, in which like characters of reference refer to corresponding

parts in the several views, the jar herein shown and denoted by the reference character 5, is preferably adapted to contain fruit or similar canned goods, and is provided with the usual exteriorly threaded mouth portion 6.

The jar closure is denoted generally by the reference character 7 consisting of an outer section 8 and an inner section 9. The outer section 8 of the cap is of substantially hollow annular form provided on its inner circumference with threads 10 adapting the outer section to have a threaded connection with the threaded mouth 6 of the jar, while the top of the outer section is provided with an enlarged circular opening 11, the walls of said opening being beveled as indicated by the character 12. Formed at points diametrically opposite the opening 11 are recesses 13 through which the extending extremities 14 of the bar 15 project, upon the initial association of the inner section 9 of the closure with the outer section 8, and thence upon a partial rotation of the inner cap section, the projecting extremities of the bar will repose upon the beveled circumference 12 of the opening of the outer section 9.

The said inner cap section 9 constitutes a disk-shaped body portion 16 having formed on the upper face 17 thereof the previously mentioned bar 15, and this bar extends for the full transverse extent of the disk and cut out at its opposite terminals to provide the same with substantially L-shaped extremities 14.

The bottom of the disk-shaped body portion is of lesser diameter than the diameter of the upper portion of the inner section of said cap, thus providing the same with an annular shoulder 18, adapted to receive the sealing gasket 19, hence upon the sealing operation of the jar, the inner cap section 9 is inserted within the mouth of said jar, reposing the gasket 19 upon the upper annular edge of said jar. After this operation, the outermost cap section 8 is placed over the inner section, the bar is inserted within the notches and given a partial rotation, thus locking the inner cap section to the outer cap section. Hence, by the screwing of the outer cap section upon the jar will serve to tightly seal the jar in such a manner as to exclude the entrance of air to the contents thereof. On the other hand, upon the opening of the closure and the outermost section has been entirely un-

screwed from the mouth of the jar, due to the locking engagement of the inner section with the outer cap section, tends to exert a pull or lifting action on the inner cap section, thus releasing the sealing gasket from the mouth of the jar. It is obvious, by providing a closure of the structure above set forth, tends to permit the sealing and unsealing of the jar in a simple and expeditious manner, and further prevents the breaking of the jar during the detachment of the closure therefrom.

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is merely illustrative, and that such changes may be made when desired as are

within the scope of the claim appended 25 hereto.

What is claimed as new, is:

A jar closure comprising an outer flanged section adapted to be screwed on the neck of the jar and formed in the top thereof with 30 an opening, an inner section fitting loosely within the outer section having a reduced lower portion extending within the mouth of the jar, a gasket carried by the reduced lower portion of said inner section, a bar 35 formed on the top of the inner section provided with L-shaped extremities having interlocking connection with the flanged outer section for permitting of the lifting of the gasket from the jar upon the removal of the outer section therefrom, and a pair of diametrically arranged spaced notches formed in the flange of the outer section of said cap 40 for permitting of the connection or disconnection of the inner section therefrom.

In testimony whereof I affix my signature.

HARRY WEAVER.
